H. G. BAXTER

FUSE MECHANISM

Filed Jan. 20, 1921

WITNESSES:

INVENTOR

J. P. Wurmbr.
J. H. Wendig.

UNITED STATES PATENT OFFICE.

HAROLD G. BAXTER, OF BALDWIN, NEW YORK, ASSIGNOR TO WESTINGHOUSE ELECTRIC & MANUFACTURING COMPANY, A CORPORATION OF PENNSYLVANIA.

FUSE MECHANISM.

Application filed January 20, 1921. Serial No. 438,572.

My invention relates to fuse mechanism and particularly to fuse mechanism employed on panel boards and like structures.

One object of my invention is to provide 5 a fuse mounting for panel boards wherein the fuses are mounted upon a carrier which serves as a closure for openings provided in the panel cover opposite the fuse receptacles and wherein the fuse supports engage 10 the standard fuse clips usually mounted upon the panel board. By reason of this construction, the fuses are removed with the carrier or closure member without the use of tools and are, consequently, disconnected 15 from contact with the live fuse clips before access to the fuses is obtainable. The fuses may, therefore, be conveniently replaced without danger of the operator coming in contact with the live terminals.

20 Another object of my invention is to provide a fuse carrier, having the above characteristics, wherein simple one-piece fuse clips are mounted on the inner side of the carrier and are provided with convolutions 25 constituting a receptacle for the fuse and a contact portion similar in shape and dimensions to the shape and dimensions of a standard cartridge fuse for engaging standard fuse clips.

30 It has been customary to mount the fuse clips on a panel board opposite the openings provided in the cover for the purpose of permitting access to the fuses for inspection or replacement. In order to replace a 35 fuse, a tool, commonly known as "fuse tongs," was usually inserted through the openings in the cover. In this method of operation, there is always danger of the tongs engaging one of the live fuse clips or 40 terminals. This unsafe method of changing the fuses is avoided by the use of fuse carriers made and operated in accordance with my invention.

Another object of the invention is to provide 45 a fuse carrier wherein the clip member may be stamped from sheet metal by simple and inexpensive stamping operations.

These and other objects, that will be made 50 apparent throughout the further description of the invention, are attained by means of apparatus hereinafter described and illustrated in the accompanying drawings, wherein:

Figure 1 is a side elevational view of the 55 apparatus embodying my invention, show-

ing the fuse carrier in disengaged relation to the fuse clips;

Fig. 2 is an end elevational view of the apparatus shown in Fig. 1, showing the fuse carrier in operative engagement with the 60 fuse clips.

Referring to the drawings, 3 represents a portion of the insulating base or panel upon which various electrical fixtures, such as 65 switches and fuses, are mounted. The front of the panel is protected by means of a cover 4 that is mounted in spaced relation with respect to the panel or base 3 and between which the usual electrical equipment is mounted.

70 The cover, which is usually made of sheet metal, is provided with an opening or openings 5 disposed opposite the fuse-clip members 6. The fuse-clip members 6 are of standard construction and each comprises a 75 single piece of metal stamped in U-shape having resilient branches 7 so curved as to form a substantially circular lamp in which the cylindrical contact members of a cartridge fuse are inserted. Two fuse clips are 80 usually mounted upon the base 3 by means of screws and are disposed in spaced relation in such a manner that they receive a support and a cartridge fuse between them. It is the usual practice to arrange the sets 85 of fuse clips side by side upon the panel, as illustrated in Fig. 2.

It has been customary to insert the fuse members in the clips 7 and to close the opening 5 in the cover by a door that normally 90 closes the opening and precludes access to the fuse members. This construction necessitates the use of fuse tongs for replacing the fuses.

95 It is an object of this invention to eliminate the necessity for using the usual fuse tongs and, with this object in view, I have provided a fuse carrier 8 which comprises a block 9, made of insulating material, which is provided with a handle 10 that may be 100 gripped by the operator when it is desired to change the fuses. The dimensions of the carrier are such that it completely closes the opening 5 when in operative position, as illustrated in Fig. 2.

105 The inner side of the carrier 8 is provided with two sets of fuse-supporting clips 11, each clip comprising a single piece of sheet metal of U-shape, the branches thereof being provided with convolutions constituting 110

a substantially circular socket portion 13 and a substantially circular terminal portion which constitute a yielding plug 14 that is adapted to be inserted between the branches 7 of the fuse clip 6.

By reason of the extension or plug 14, the carrier 8 is supported in predetermined closed relation to the cover 4. In operation, fuses 15 are preferably inserted within the 10 sockets 13, and the carrier 8 is then shoved through the opening 5 to the position shown in Fig. 2, wherein the plug portions 14 of the supporting members 11 are in operative engagement with the clip members 6. In 15 order to replace a fuse, it is necessary merely to withdraw the carrier 8 from the cover, which operation, disconnects the fuses from the fuse clip members 6. The fuses may then be conveniently replaced and the 20 carrier again inserted.

It will be obvious that the fuses 15 may be inserted between the free ends of the branches, forming the plug 14, and that two 25 fuses may be placed in each clip in order to increase the capacity of the fuses in the circuit. The construction is extremely simple, it being practicable to readily mold the carrier member of plastic insulating material, and the fuse supporting members 11 may be 30 stamped from sheet metal by simple, inexpensive stamping operations.

While I have described and illustrated but one embodiment of my invention, it will be 35 apparent to those skilled in the art that various changes, modifications, substitutions, additions and omissions may be made in the apparatus illustrated without departing from the spirit and scope of the invention, as set forth in the appended claims.

40 I claim as my invention:—

1. In a panel board, the combination with a board having a fuse clip thereon and a cover having an opening opposite the fuse clip, of a carrier for closing the opening and 45 provided with a clip for yieldingly and re-

leasably supporting a fuse thereon, the said clip having portions extending beyond the fuse for engaging the interior of the fuse clip on the board for preventing release of the fuse from the carrier when the carrier is 50 in closed position.

2. A fuse carrier comprising an insulating block and a clip having yielding arms for gripping a cartridge fuse between them, the said arms having yielding extensions formed 55 in conformity with the contact terminal of a standard fuse and adapted to yieldingly engage the interior of a cartridge fuse clip for supporting the said fuse in operative relation with the standard clip.

3. The combination with a pair of separate standard fuse receptacles disposed in spaced relation, of a fuse carrier having fuse-supporting members disposed in spaced relation thereon for yieldingly engaging the 60 said fuse receptacles whereby the carrier is supported in a predetermined relation with the receptacles, the said supporting members being provided with sockets for detachably receiving and supporting fuse elements in 65 electrical engagement therewith.

4. The combination with a standard receptacle for a cartridge fuse having a pair of yielding contact arms for supporting a standard fuse between them, of a carrier for a cartridge fuse having contact arms for gripping a fuse between them and having yielding contact portions extending beyond the fuse and conforming in contour to that of a standard fuse terminal, for engaging 70 the interior of the receptacle, whereby the contact arms of the carrier are pressed inwardly into conductive contact with the terminal of the fuse, and whereby the carrier is detachably supported in a predetermined 75 position with respect to the receptacle.

In testimony whereof, I have hereunto 80 subscribed my name this eleventh day of January 1921.

HAROLD G. BAXTER.
